S. & T. CHAMPION.
PADDLE WHEEL.

No. 10,359.

Patented Jan. 3, 1854.

UNITED STATES PATENT OFFICE.

SAMUEL CHAMPION AND THOMAS CHAMPION, OF WASHINGTON, DISTRICT OF COLUMBIA.

IMPROVEMENT IN FEATHERING PADDLE-WHEELS.

Specification forming part of Letters Patent No. 10,359, dated January 3, 1894.

To all whom it may concern:

Be it known that we, SAMUEL CHAMPION and THOMAS CHAMPION, of the city and county of Washington, in the District of Columbia, have invented certain new and useful Improvements in Propellers for Vessels; and we do hereby declare that the following is a full, clear, and exact description of the construction and operation of the same, reference being had to the annexed drawings, making a part of this specification, and in which—

Figure 1 represents an elevation of our improved propeller; Fig. 2, an inverted view of the same; Fig. 3, an elevation of the propeller as adapted to turn in a direction opposite to that of Fig. 1; Fig. 4, a perspective view of one of the double paddles detached; Fig. 5, a section through the hub or shaft to show the shank of the blades or paddles passing through the same; Fig. 6, a perspective view of the cam-frame for automatically shifting the paddles upon their shanks, and Fig. 7 an end view of the propeller embracing a modification of our improvement.

Letter A represents a portion of the guard or frame-work of the vessel, which supports the shaft of the propeller; B, the shaft; C, the blades or paddles; D, the hub; E, the shank or arm which connects the blades; F, oblong projections on the shank of each blade, by which the feathering of each blade is partially effected; G, the cam-guides, stationary except when moved to reverse the motion of the propeller, by which, in connection with the oblong buttons F, the feathering of the blades is completed; H, the arms of the cam-frame, to which the guides G are attached, and by reversing which to the opposite side of the guard-frame the paddles are placed in position for effective operation in an opposite direction, and by dropping said arms to the perpendicular in the water the lower blades will all be brought to a feathered position, so as to offer but little resistance to the sailing of the vessel when by accident or otherwise the propeller may not be used; I, the boss of the cam-guides, fitted to the shaft B in a manner similar to ordinary eccentrics, or as represented in the inverted view, Fig. 2, and in the perspective view, Fig. 6.

The distinguishing features in this propeller are—

First. The continuous arm or arms passing directly through the hub or shaft, with a blade at each end fixed at right angles with each other, so that in feathering the lower blade in the water after it has exerted all its propelling force the same act shall without any further arrangement place the upper blade in full position for efficient action. Any number of arms and blades may be added by extending the cam arrangement.

Second. The hub may be of any size required by resorting to open instead of solid work, as represented in Fig. 7, wherein any desired number of spokes may be used. This form is particularly advantageous where large vessels are to be propelled, inasmuch as the leverage or bearing of the arms may be increased to any size, this form admitting more than double the leverage as where the arms only radiate from near the center. The arms may be made in parts and put together by sockets and keys, as at letter K, Fig. 7, so as to be easily inserted and separated for repair. When made on this form, the center of the arm may be considerably smaller, as shown by the dotted lines, there being but little force exerted there beyond what is necessary to keep the blades in their right-angled position and to resist the twist in feathering the blades, the bearing being chiefly at the periphery of the rim.

Third. The double blade on one shank, with more than double the length of bearing through the hub or rim as where single blades not reaching quite to the center are used, a counter-balance is produced, and the turning is effected with less force and friction in consequence thereof. This, with the fact that by turning the lower blade also turns the upper and thereby saves half the friction of turning in any form where the blades are not on one connected arm and at right angles, renders this form particularly simple and advantageous. The friction, though less in this than most other plans, may be still further reduced by the application of anti-friction rollers.

We claim no particular shaped blades for our paddles, as various shapes may be used; but as a general principle we prefer, where it can be applied, the narrow oar-shaped blade, reaching deep into the denser water, so as to

make the engine labor in forcing it through without much disturbing the surface. We are encouraged in this view by the narrow oar, the fins of the fish, and particularly by the long deep propellers of the deer, that animal being among the very fastest of swimmers as well as of runners. In making these blades we would propose as the best material wrought-iron or steel, or both, with the oblong button or guide at the shank end of the blade forged solid, the blade next thereto being round, or nearly so, thence outwardly being flattened and widened, leaving the center the thickest and strongest, by which means great strength will be attained.

It is obvious that various modifications may be made in the construction of this propeller without departing from the principle of our

invention, and we also propose to use it either as partially or wholly submerged.

What we claim as our invention, and desire to secure by Letters Patent, is—

The continuous arm or arms through the shaft, hub, or rim, with a blade on each end thereof placed permanently at right angles to each other, so that when one is feathered in the water the other is placed in proper position for propulsion by that act, also the reversing cam-frame, in combination with the oblong projections at the shank of the blades.
